UNITED STATES PATENT OFFICE.

JOEL ALBERT GROVER, OF WOODLAND, WASHINGTON.

HOP-WIRE-DETACHING DEVICE.

No. 873,227.

Specification of Letters Patent.

Patented Dec. 10, 1907.

Application filed October 19, 1906. Serial No. 339,726.

To all whom it may concern:

Be it known that I, JOEL ALBERT GROVER, a citizen of the United States, and a resident of Woodland, in the county of Cowlitz, State 5 of Washington, have invented a new and useful Hop-Wire-Detaching Device, of which the following is a specification, reference being had to the accompanying drawings as constituting a part thereof.

10 This invention relates to the so-called "trellis system" of wiring hop yards, such wiring-system consisting in fastening a series of wires lengthwise over the hop field and suspending therefrom, by dependent hooks, 15 a series of cross wires; and my invention has for its object to provide an implement by the use of which the cross-wires may be conveniently detached from their suspending hooks, so as to allow the cross-wires and the 20 vines thereon, to drop down within convenient reach of the hop pickers.

I attain my object by the device illustrated in the drawings and comprising a pole having affixed to its upper end the means 25 which may be operated to lift and disengage a cross-wire from the hook by which it is suspended from a longitudinal wire; the device embodying the features and operating as hereinafter particularly set forth:

30 In the drawings: Figure 1 is a side elevation of my device, arranged in oblique position, so as to show a greater portion thereof within the limited drawing-field; Fig. 2 is a section of the operating part of my device, 35 removed from its pole; Fig. 3 is a cross section, taken on a line $x-x$ of Fig. 1; and Fig. 4 is a perspective detail of the arrangement of certain parts of my device, as will be hereinafter more fully described.

40 Referring now to the reference characters in the drawings: The pole a , of wood, has mounted on its upper end the wire-lifting and detaching devices. These may consist of a tubular shank d , made with a collar c , 45 having an interior thread, in which is inserted a socket b , in which the pole a is inserted. On the upper end of such tubular shank is a head e , made with lateral portions constituting shoulders g , g , the extremities g' 50 of which are made with downward receding curves as shown, for the purpose below described. The head e is further made with an upwardly projecting piece e' having a perforation e^3 , and right-angle flanges e^2 . To the 55 head e , is removably affixed a knife-blade f , which is provided to cut down such "bou-

quets" or bunches of hop-flowers as may be twined around the longitudinal wires. The knife-blade is removably fastened by means of a sleeve h . The latter may be made of one 60 piece, as shown in Fig. 3, or in two parts, h' , h^2 , as shown in Fig. 4. In the last mentioned construction the two parts h' , h^2 , are made with flanged ends h^3 , respectively, and the two parts are adapted to fit one into the 65 other. The sleeve h is made with a perforation h^4 to receive a bolt, inserted through all the parts when assembled, and thereby securely fastening the knife-blade in place.

The head e may be made detachable, as 70 shown in Fig. 2, if preferred, so as to simplify the manufacture of my device, although I deem it just as simple if such head e be made an integral part of the tubular shank b . When the head is made detachable, the 75 shank b is provided with a threaded socket t , and the head e with a threaded stud e^1 . The head e is further provided with transversely projecting fingers i , i , which are integral parts of the sleeve h . Straddling the shank 80 d , is pivoted, by a pin d' , a forked lever k , the end k' of which is connected by links p , p , with a sleeve or tubular-lifter r , having a flaring upper end or mouth r' ; the latter being adapted to allow such lifter to be moved 85 part way up on the head e , as shown in Fig. 1. To connect the links p with the lifter r , the base of the latter is made with hinge-knuckles q . Straddling the lower end of the pole a , is pivoted, by a pin o , a lever n , connected by a rod m , to the end k^2 of the lever k . On the shank d , within the tubular lifter r , is arranged a coil-spring s , the lower end of which bears on the interior of the base of the lifter, and the upper end thereof bearing 90 against an abutment for that purpose provided on the shank d , which, as the construction is illustrated in my drawings, consists of the collar t . The head e is made with an opening e^5 to receive the upper end of the 95 hook u , as shown in Fig. 4.

The operation of my device is as follows: Let l , represent one of the main or longitudinal wires of the hop-yard, and l' one of the cross-wires suspended from the former 105 by hooks u . My device will be held under a hook u , in such position that one of the fingers i of the head e will project over and engage with a main wire l , and that the mouth of the lifter r , will be immediately under a 110 hook u , approximately as shown in Fig. 2. By now depressing the lever n , the co-operat-

ing devices will be caused to raise the lifter *r*, during which action the hook *u*, will enter the mouth of the lifter. And continuing the described action of my device the lifter *r*, will 5 finally lift the cross-wire *l* out of the lower end of the hook *u*, because such lower end will be engaged, and moved inward by the contact of the mouth of the lifter therewith, while the curved-portion *g'* of the head *e* 10 will coöperate with the rim of the lifter to force the cross-wire out of the opening of the lower end of the hook *u* and cause such cross-wire to clear my implement and drop down. On releasing the lever *n*, the spring 15 *s*, will operate to return the parts to their normal position.

When engaging the main wire with one of the fingers *i*, of the head *e*, care must be taken to so manipulate the implement as to 20 cause the upper-end of the hook *u* to enter the opening *e*³ in the head, so that in raising the lifter the hook *u* will pivot on the main wire and the lower end thereof be moved outward by contact of the cross-wire with 25 the edge *g'* of the head *e* as above described.

I claim:

1. In a device of the character described, the combination of a shank, a head on the upper end thereof, the upper part of which 30 head is provided with laterally projecting shoulders and the portions below the shoulders receding downward, said head also having a central aperture, fingers as *i* projecting transversely from the sides of the head, a 35 spring-controlled sleeve-like lifter having a flaring mouth adapted to be raised over the base of the head, said lifter being normally below said head, and lever-like means whereby to raise the lifter.
- 40 2. In a device of the character described, the combination of a pole, a tubular shank mounted thereon, a head on the end of the shank, the upper part of which head is provided with laterally projecting shoulders and 45 the portions below the shoulders receding downward, said head also having a central aperture, fingers as *i* projecting transversely from the sides of the head, a sleeve-like lifter having a flaring mouth adapted to be raised 50 over the base of the head, interior shoulders at the base of the lifter, a collar on the shank at the upper end of the lifter, a coil-spring seated between said shoulder and collar to normally hold the lifter down, a forked lever

pivoted on the shank, one end thereof connected to the lifter, a forked handle pivoted on the pole, a rod connecting said lever and handle; the parts being so arranged that depressing the handle will raise the lifter. 55

3. A device of the character described, 60 comprising a pole, a tubular shank mounted thereon, a head on the upper end of the shank, the upper part of which head is provided with laterally projecting shoulders and the portions below the shoulders receding 65 downward, said head also having a central aperture, fingers as *i* projecting transversely from the sides of the head, a sleeve-like lifter having a flaring mouth adapted to be raised over the base of the head, interior shoulders 70 at the base of the lifter, a collar on the shank at the upper end of the lifter, a coil-spring seated between said shoulder and collar to normally hold the lifter down, a forked lever pivoted on the shank, one end thereof connected to the lifter, a forked handle pivoted on the pole, a rod connecting said lever and handle; the parts being so arranged that depressing the handle will raise the lifter, and 75 said head being also provided with a knife, 80 for the purpose described.

4. A device of the character described, 85 comprising a pole, a tubular shank mounted thereon, a head on the upper end of the shank, the upper part of which head is provided with laterally projecting shoulders and the portions below the shoulders receding 90 downward, said head also having a central aperture, fingers as *i* projecting transversely from the sides of the head, a sleeve-like lifter having a flaring mouth adapted to be raised over the base of the head, interior shoulders 95 at the base of the lifter, a collar on the shank at the upper end of the lifter, a coil-spring seated between said shoulder and collar to normally hold the lifter down, a forked lever pivoted on the shank, one end thereof connected to the lifter, a forked handle pivoted on the pole, a rod connecting said lever and handle; the parts being so arranged that depressing 100 the handle will raise the lifter, and said head being also provided with a socket for the purpose of receiving a knife.
